J. KEANE,

Air-Vent for Casks.

No 25,606.

Patented Sept. 27, 1859.

UNITED STATES PATENT OFFICE.

JOHN KEANE, OF NEW YORK, N. Y., ASSIGNOR TO HIMSELF AND ANDREW McLEAN WOOD, OF SAME PLACE.

IMPROVEMENT IN BUNGS OF CASKS.

Specification forming part of Letters Patent No. 25,606, dated September 27, 1859.

To all whom it may concern:

Be it known that I, JOHN KEANE, of the city, county, and State of New York, have invented a new and useful Improvement in Bungs and Spigots for Casks containing Beer, Cider, and other Liquors; and I do hereby declare that the following is a full, clear, and exact description of the same, reference being had to the accompanying drawings, forming part of this specification, in which—

Figure 1 is a vertical central section of a bung for a lager-beer cask with my invention applied. Fig. 2 is a horizontal section of the same. Fig. 3 is a vertical section on a larger scale than Figs. 1 and 2 of the portion of the bung containing the valve. Fig. 4 illustrates the application of the invention to a spigot.

Similar letters of reference indicate corresponding parts in the several figures.

My invention consists in providing a bung or spigot with a reservoir to contain proof spirit, or other spirituous liquor, and with a suitable system of pipes or passages to cause all the air admitted to the cask to pass through the spirit or spirituous liquor in the reservoir, for the purpose of being impregnated with alcoholic vapor, which in a great degree counteracts its injurious action upon the liquid in the cask, and so enables the said liquid to be kept on draft for a longer time in good condition.

It also consists in a certain arrangement of a valve, in combination with the aforesaid reservoir, applied to a bung or spigot for the purpose not only of admitting air to take the place of the liquid drawn off, but of preventing the escape of gases from the cask.

To enable others skilled in the art to make and use my invention, I will proceed to describe its construction and operation.

In applying my invention to a bung I construct the reservoir within the bung itself by making the same of metal, and hollow, the space within it constituting the reservoir, and as a matter of convenience, I make the bung in two pieces—viz., a hollow shell, A, formed to fit the bung-hole, and with a large head which enables it to be laid hold of by the hand, to place it in and remove it from the bung-hole of the cask C, and a concave cover,

B, which screws into the upper or outer end of the said shell.

a is the inlet-pipe, screwed into the head B, and opening into the reservoir near the bottom thereof; and b is the outlet-pipe for permitting the escape of air from the bung into the cask, said pipe screwing into the bottom of the bung and extending upward nearly to the top thereof. The reservoir is filled with pure spirit, or any spirituous liquor, nearly to the mouth of the pipe b. By this arrangement of the inlet and outlet pipes of the reservoir all the air admitted to the cask C, to fill the vacuum produced by drawing off the liquid from the cask, is caused to pass, as indicated by arrows in Fig. 1, through the spirit in the reservoir, and so caused to take up in suspension in it some of the spirit, which, by its preservative effect, is caused in a great degree to counteract or neutralize the action of the air upon the liquid in the cask.

c is the valve for admitting air to the reservoir and preventing the escape of gases therefrom, made of india-rubber or other flexible material, and fitted over an opening, e, in a box, d, which is attached to the upper and outer end of the inlet-pipe a, outside of the reservoir.

f is a cap screwing into the box d to secure the valve in its place, and serving by its removal to permit the introduction and removal of the valve. All the air admitted to the inlet-pipe a has to pass through the opening e and valve c, the latter being opened inwardly to the box d, as shown in Fig. 1, by the pressure of the atmosphere, to permit the entrance of air to the pipe a, when a vacuum is produced in the cask by drawing off the liquid, but is closed by its own elasticity, as shown in Fig. 3, so soon as an equilibrium is established between the air or gases in the cask and the external atmosphere, and so prevents the escape of carbonic acid from the tank.

In applying the invention to a spigot a reservoir of suitable shape, with a similar system of pipes, valve-box, and valve to those of the bung, is constructed, and the pipe b is extended below the bottom of the reservoir, as shown at b' in Fig. 4, to constitute the spigot, which is screwed into or otherwise tightly inserted in the vent-hole of the cask.

What I claim as my invention, and desire to secure by Letters Patent, is—

1. Providing a bung or spigot with a reservoir for spirit, and a system of pipes or passages, *a b*, or their equivalent, so arranged as to cause all the air entering the cask to pass through the spirit in said reservoir, substantially as and for the purpose specified.
2. In combination with such a reservoir and

system of pipes and passages, or their equivalents, a valve, *c*, applied to the bung or spigot, substantially as and for the purpose herein specified.

JOHN KEANE.
